OF HOPEDALE, MASSACHUSETTS, A CORPORATION OF MAINE.

FEELER MECHANISM FOR LOOMS.

1,387,320.

Specification of Letters Patent. Patented Aug. 9, 1921.

Application filed October 7, 1919. Serial No. 328,976.

To all whom it may concern:

Be it known that I, ISAAC SNOW, a citizen of the United States, residing at Lawrence, in the county of Essex and State of Massachusetts, have invented an Improvement in Feeler Mechanism for Looms, of which the following description, in connection with the accompanying drawings, is a specification, like characters on the drawings representing like parts.

This invention relates to feeler mechanism for looms, and more particularly to that type of feeler mechanisms wherein the feeler is given a movement longitudinally of the shuttle when the filling is substantially exhausted. One of the objects of the present invention is to provide a feeler mechanism of the type wherein the feeler is given a movement longitudinally of the shuttle when the filling is substantially exhausted, which shall be simple in construction, effective and sensitive in operation. To these ends, an important feature of the present invention consists in a feeler which is mounted upon a filling carrier for bodily movement relative thereto in a direction longitudinally of the shuttle when the filling is substantially exhausted. To insure the bodily movement of the feeler under the conditions stated, the present invention further contemplates the provision of a feeler relieving member which, after the feeler has engaged the surface within the shuttle, is met by a surface on the lay to relieve the pressure against the feeler incident to movement of the feeler carrier forwardly on a detecting beat.

Another feature of the invention consists in a feeler having a movement toward and from the front of the loom relative to the carrier, and a bodily movement on the carrier in a direction longitudinally of the shuttle under the impulse of a spring which effects such movement of the feeler when the filling is substantially exhausted during the beat-up movement of the lay, and cam means for returning the feeler bodily to its feeling position as the lay retreats.

The above general features of the present invention as well as other novel combinations of parts will be best made clear by the following description in connection with the accompanying drawings which present a good practical embodiment of the present invention.

In the drawings:

Figure 1 is a perspective view of the feeler side portion of the loom, some of the parts being omitted;

Fig. 2 is an enlarged detached plan view showing the action of the feeler mechanism when a working supply of filling is present in the shuttle on a detecting beat;

Fig. 3 is a view similar to that of Fig. 2 showing the action of the feeler mechanism when the filling is substantially exhausted; and

Fig. 4 is a detached detail perspective view showing the rear portions of the feeler and feeler relieving member.

The feeler mechanism and those features of the loom construction which are not directly associated with the present invention are not herein illustrated and described, as they are well known and understood by those skilled in the art.

The loom frame 1 has mounted thereon the brackets 2, one at each side of the loom, which support the usual transverse or rock shaft 3 from which rises the arm 4 having pivoted thereto at 5 the latch 6 whose rear end portion 7 is adapted at times to be engaged by an operating member 8 which may be either the cam follower or a part associated therewith.

The lay 9 has the usual shuttle-box 10, the front wall of which is slotted as at 11 to register with an opening 12 in the side wall of the shuttle 13 when in the detecting box. These parts may be as usual, and the shuttle may be provided with the usual filling carrier or bobbin 14.

Extending from the loom frame is the shipper stand 15 to which is connected the slotted arm 16 which may be formed as a bracket secured to the shipper stand or be cast integral therewith. Mounted on the slotted arm 16 is the bracket 17 which may be adjustably secured in place by means of a bolt 18 passing through the slot 19 of the arm 16, as will readily appear from Fig. 1.

Secured to the bracket 17 by suitable means such as the screws 20 is the feeler stand 21.

The present invention contemplates that the feeler which detects the condition of the filling in the shuttle shall be mounted on the carrier, and in the present instance of the invention, the carrier comprises a slide 22

mounted upon the feeler stand 21 for movement toward and from the front of the loom. Extending frontwardly from the feeler carrier 22 is the rod or stem 23 which passes 5 through a lug 24 carried by an arm 25 extending frontwardly from the feeler stand, and a spring 26 interposed between the carrier 22 and the lug 24 acts normally to move the carrier 22 or hold it in its rearward position as indicated in Fig. 1, wherein a stop 27, shown as a pin in the present instance, extending upwardly from the feeler stand, serves to limit the rearward movement of the feeler carrier. Suitable means in addition 10 to the rod or stem 23 may be employed to guide the feeler carrier 22 in its movements. In the present instance, the carrier is shown as slotted at 28, and a lug 29 extending upwardly from the feeler stand 21 passes 15 through the slot 28 and has a widened upper end whereby the feeler carrier 22 may be directed in its movement toward and from the front of the loom.

As hereinbefore noted, the feeler in the 20 present instance, is connected to the feeler carrier for bodily movement in a direction longitudinally of the shuttle, and is held from such bodily movement by engagement with the filling until substantial exhaustion 25 thereof. As one good practical form of means for effecting this characteristic operation of the feeler in the present invention, the carrier 22 is provided with laterally extending openings at its front and rear portions as at 30 and 31 into which extend the 30 guide pins 32 and 33 respectively. The guide pins 32 and 33 are carried by a cam member 34 which is provided with the cams 35 and 36 which are adapted to be engaged 35 by pins 37 and 27 as the feeler carrier and 40 perforce the cam member 34 move rearwardly into positions indicated in Fig. 1. A spring 38 connected at one end to the pin 39 on the feeler carrier and at its other end 45 to a pin 40 on the cam member 34, serves normally to move the cam member 34 bodily in a direction longitudinally of the shuttle, the movement of the cam member being guided by the pins 32 and 33 hereinbefore 50 described.

The cam member 34 has a lug 41 at its 55 front portion through which extends the rod or stem 42 of a feeler 43, the rear portion 44 of which is roughened or provided with teeth. The cam member 34, in the present instance of the invention, is extended rearwardly and provided with a guide pin 45 which extends into a slot 46 formed in the feeler 43. Mounted on the stem 42 of the 60 feeler is the spring 47 which may be light or of only sufficient tension to insure that the teeth or roughened portion 44 of the feeler when engaged by the filling shall sink into the filling, so that bodily movement of the 65 feeler longitudinally of the shuttle may be

prevented by the filling when a working supply of filling is present in the shuttle on a detecting beat.

The spring 47 bears at one end against the lug 41 and at its other end against a shoulder 48 formed on the feeler, the construction being such that the feeler 43 while mounted on the feeler carrier through the medium, in the present instance, of the cam member 34, is yet capable of some movement toward 70 and from the front of the loom independent of the movement of the feeler carrier and under the impulse of the light spring 47 or the pressure of the filling or surface within the shuttle against the end of the feeler. 75 80

To prevent injury to the filling by the constantly recurring impact against the toothed end of the feeler, and at the same time to relieve the feeler from undue pressure of the surface within the shuttle engaged by it, 85 the present invention provides a feeler relieving member which is connected to the feeler carrier and serves by engagement with a surface on the lay to move the feeler carrier frontwardly against the push of the 90 spring 26. In the present instance of the invention, the feeler relieving member consists of a finger 49 secured to the feeler carrier 22 and provided with a slotted rear portion 50 which embraces the rear end portion 95 of the feeler 43, as best indicated by Fig. 4. On the forward movement of the lay on a detecting beat, the rear toothed end portion 44 of the feeler will first engage the surface within the shuttle and will be moved 100 frontwardly thereby against the light tension of the spring 47 which, however, will be sufficient to insure that the teeth or roughened end 44 of the feeler shall sink into the filling when a working supply of filling is 105 present. As the lay continues its forward movement, the rear end portions 51 and 52 of the feeler relieving member will themselves engage the surface within the shuttle and serve to move the feeler frontwardly, 110 thus leaving the feeler 43 free to assert its detecting action at all stages of the operation.

Should a working supply of filling be 115 present in the shuttle on a detecting beat, as indicated in Fig. 2, the toothed end portion 44 of the feeler will engage the filling and sink into it sufficiently to prevent bodily movement of the feeler 43 in a direction longitudinally of the shuttle under the impulse of the spring 38 as the feeler carrier and cam member 34 are moved frontwardly by the forward push of the surface on the lay against the feeler relieving member 49. Should, however, the filling be substantially 120 exhausted on a detecting beat, as indicated in Fig. 3, the filling will no longer be able to restrain bodily movement of the feeler in a direction longitudinally of the shuttle 125 as the lay beats up, consequently, when the 130

cam member 34 is moved frontwardly by the frontward movement of the feeler carrier 22, and out of range of the pins 27 and 37, the spring 38 will assert itself and cause 5 bodily movement of the feeler in a direction longitudinally of the shuttle, such movement being defined and guided by the guide pins 32 and 33 hereinbefore referred to.

This bodily movement of the feeler longitudinally of the shuttle on a detecting beat, 10 indicates that the filling is substantially exhausted, and that replenishment of filling should be effected. To do this, the present invention utilizes this bodily movement of 15 the feeler longitudinally of the shuttle to set in action a train of mechanism for effecting replenishment of filling. In the present instance of the invention, the feeler stand has pivotally mounted thereon at 53 a lever 54 adapted to be moved about its pivotal 20 mounting by the bodily side movement of the feeler under the push of one of the guide pins such as 33 (Fig. 3). The lever 54 is connected to the transmitter 55, the opposite 25 end of which is connected at 56 to a lever 57 pivoted at 58 to a stand 59 rising from the loom frame. The lever 57 has an arm or finger 60 which underlies the latch 6, the construction being such that when the feeler is 30 moved bodily in a direction longitudinally of the shuttle on a detecting beat, the lever 54 will be moved from the position indicated in Fig. 2 to that of Fig. 3, thereby actuating the lever 57 to lift the latch 6 and place its 35 end 7 in the path of movement of the operating member 8, which on its frontward movement effects a rocking action of the transverse shaft 3 to effect replenishment of filling by the usual filling replenishing mechanism which is not herein shown.

What is claimed is:—

1. In a feeler mechanism for looms, a feeler carrier movable toward and from the front of the loom on each detecting beat, a 45 feeler relieving member connected to the feeler carrier and adapted to be engaged by a surface on the lay for moving the feeler carrier frontwardly on each detecting beat, a cam member mounted for lateral movement on the feeler carrier, a spring acting to move the cam member laterally on the feeler carrier, a feeler mounted on the cam member and adapted to be held from movement laterally of the feeler carrier by engagement of the filling until the latter is substantially exhausted, and means actuated by bodily movement of the feeler in a direction longitudinally of the shuttle to effect replenishment of filling.

60 2. In a feeler mechanism for looms, a feeler carrier mounted independently of the lay and movable toward and from the front of the loom on each detecting beat, a feeler relieving member connected to the feeler carrier and adapted to be engaged by a sur-

face on the lay to effect frontward movement of the carrier on each detecting beat by frontward pressure of said surface, a feeler mounted on the carrier for yielding frontward movement thereupon and to engage a 70 surface within the shuttle in advance of the feeler relieving member, guiding means between the feeler and carrier for directing bodily movement of the feeler in a direction longitudinally of the shuttle, a spring for 75 effecting such movement, and cam means acting in opposition to the spring to return the feeler bodily to initial feeling position.

3. In a feeler mechanism for looms, the combination of a feeler carrier independent 80 of the lay and mounted for movement toward and from the front of the loom, a feeler relieving member for engaging a surface on the lay on each detecting beat to impart the frontward movement of the lay to 85 the carrier, a feeler connected to the carrier for bodily movement frontwardly upon the carrier and in a direction longitudinally of the shuttle and held from such longitudinal movement until the filling is substantially 90 exhausted, and a spring for moving the feeler bodily on the carrier in a direction longitudinally of the shuttle when the filling is substantially exhausted.

4. In a feeler mechanism for looms, the 95 combination of a feeler carrier mounted independently of the lay, a feeler supported by the carrier for movement frontwardly relative to the carrier and in a direction longitudinally of the shuttle, a feeler relieving 100 member connected to the carrier for effecting frontward movement of the carrier on each detecting beat by the frontward push of a surface on the lay, and a spring for moving the feeler bodily on the carrier when the filling is substantially exhausted.

5. In a feeler mechanism for looms, the combination of a feeler carrier mounted independently of the lay, a feeler relieving member for engaging a surface on the lay and 110 moving the carrier frontwardly on each detecting beat due to the frontward pressure of said surface, a spring normally acting in a rearward direction upon the carrier to return it to rearward position, a feeler connected 115 to the carrier for bodily movement thereon in a direction longitudinally of the shuttle and held from such movement by engagement with the filling until the filling is substantially exhausted, and a spring for moving the feeler on the carrier when the filling is substantially exhausted.

6. In a feeler mechanism for looms, a feeler carrier mounted independently of the lay for movement toward and from the front 125 of the loom on each detecting beat, a feeler mounted on the carrier for yielding frontward movement relative to the carrier and for sliding bodily movement relative to the carrier in a direction longitudinally of the 130

shuttle and held from such longitudinal movement by the filling on a detecting beat until substantial exhaustion thereof, and a 5 feeler relieving member connected to the carrier for effecting frontward movement thereof by the frontward push of a surface on the lay on each detecting beat.

7. In a feeler mechanism for looms, a feeler carrier mounted independently of the 10 lay for movement toward and from the front of the loom on each detecting beat, a feeler mounted on the carrier for movement therewith and for bodily movement relative thereto in a direction longitudinally 15 of the shuttle and held from such movement by the filling on a detecting beat until substantial exhaustion thereof, a feeler relieving member connected to the carrier for effecting frontward movement thereof by 20 the frontward push of a surface on the lay on each detecting beat, and cam means operable upon movement of the carrier rearwardly to impart later movement to the feeler.

25 8. In a feeler mechanism for looms, the combination of a feeler carrier mounted independently of the lay, a feeler connected to the carrier for frontward movement therewith and yielding frontward movement relative thereto, and also for bodily 30 movement relative to the carrier in a direction longitudinally of the shuttle, a feeler relieving member connected to the carrier and effecting frontward movement thereof 35 by the push upon the relieving member following engagement of the feeler with the surface within the shuttle, and means for moving the feeler longitudinally of the shuttle when it is detects substantial exhaustion of filling.

40 9. In a feeler mechanism for looms, the combination of a feeler mounted independently of the lay for bodily sliding movement longitudinally of the shuttle but 45 held from such bodily movement by the filling until substantial exhaustion thereof

and movable toward and from the front of the loom on each detecting beat, a feeler relieving member adapted to be moved frontwardly by a surface within the shuttle 50 after the feeler has engaged the said surface, and connections between the feeler and the feeler relieving member for effecting frontward movement of the former by the latter on each detecting beat. 55

10. In a feeler mechanism for looms, the combination of a feeler mounted independently of the lay for bodily sliding movement longitudinally of the shuttle but held from such bodily movement by the 60 filling until substantial exhaustion thereof and movable toward and from the front of the loom on each detecting beat, a feeler relieving member adapted to be moved frontwardly by a surface within the shuttle 65 after the feeler has engaged the said surface, a light spring for yieldingly holding the feeler with its rear end extending beyond the rear end of the feeler relieving member, and connections between the feeler and the 70 feeler relieving member for effecting frontward movement of the former by the latter on each detecting beat.

11. In a feeler mechanism for looms, the combination of a feeler carrier mounted independently of the lay and for movement toward and from the front of the loom, a feeler supporting member interposed between the feeler and feeler carrier, a feeler yieldingly mounted on the supporting member, a spring normally acting between the feeler supporting member and feeler carrier and tending to move the feeler supporting member relative to the feeler carrier in a direction longitudinally of the shuttle, and 80 a relieving member extending rearwardly from the feeler carrier to engage a surface carried by the lay and relieve the pressure against the feeler on a detecting beat. 85

In testimony whereof, I have signed my 90 name to this specification.

ISAAC SNOW.
